His Attorney.

UNITED STATES PATENT OFFICE

2,250,195

ELECTRIC CIRCUIT INTERRUPTER

Benjamin R. Hermann, Lanesborough, Mass., assignor to General Electric Company, a corporation of New York

Application August 31, 1939, Serial No. 292,852

11 Claims. (Cl. 200—114)

The present invention relates to electric circuit interrupters, and more particularly to circuit interrupters, such as, for example, drop-out fuse cutouts, which incorporate a movably mounted switching unit including an insulating holder for supporting an automatically operable circuit interrupting means, together with mechanism capable of functioning automatically upon operation of the circuit interrupting means to effect movement of an element or elements of the switching unit from an operative position to a dropped-out position or other position giving indication of circuit interruption.

The invention has for one of its objects the provision, in a circuit interrupter such as referred to above, of improved construction and arrangement of supporting and latching mechanism whereby release of the switching unit from an operative position upon operation of the circuit interrupting means is effected without the necessity for movement of the insulating holder of the switching unit.

Another object is the provision, in a drop-out circuit interrupter of the enclosed type, of improved mechanism whereby release of the switching unit from operative position upon operation of the circuit interrupting means is effected in response to movement of a cover or door of the casing of the circuit interrupter, and independently of movement of the insulating holder forming part of the switching unit.

A further object of the invention is the provision of improved contact mechanism particularly applicable to drop-out circuit interrupters but not necessarily limited to such application.

The invention has for an object also the provision of improved apparatus for carrying out certain features of the invention disclosed and more broadly claimed in United States Letters Patent 2,197,646, granted April 16, 1940, upon an application of George F. Lincks and assigned to the same assignee, as the present invention.

Other objects and the details of that which I consider to be novel and my present invention will become apparent from the following description and the claims appended thereto, taken in conjunction with the accompanying drawing wherein are shown exemplary embodiments of my invention as applied to fuse cutouts of the enclosed drop-out type.

In the drawing, Fig. 1 is a side elevation, partially in section, of an exemplary form of fuse cutout incorporating one embodiment of my invention, the parts being shown in normal operative positions; Fig. 2 is a partial view of the cut-

out of Fig. 1, showing the parts thereof after circuit interrupting operation; Fig. 3 is a sectional plan view along the line 3—3 of Fig. 1; Fig. 4 is a detail view of a part of the mechanism of Fig. 1; Fig. 5 is a side elevation, partially in section, of a fuse cutout incorporating a second embodiment of my invention, with the parts in normal operative positions; and Figs. 6, 7, and 8 are detail views of a modified form of latching and contact making mechanism suitable for carrying out my invention.

The cutout shown in Figs. 1—4 of the drawing, has a casing 10 which is constructed of porcelain, glass, or other suitable insulating material 15 and which has an integrally formed electric creepage and gas barrier 11 on the inner rear wall thereof. The casing is provided with a rearwardly extending mounting bar 12 for attachment to an electric line pole and cross-arm structure, or other suitable supporting means. Terminals 13 and 14 are attached on the inner rear wall of the casing respectively above and below barrier 11 and are provided with suitable clamping means, indicated at 15, for attachment of line conductors or leads thereto. Upper terminal 13 has a generally U-shaped contact clip 16, the resilient arms of which extend in spaced substantially parallel relationship toward the front of casing 10, as will be seen best from Fig. 3. The lower terminal 14 has a similar U-shaped contact clip 17. Pivotedly supported within casing 10 is a switching unit which comprises in the main an elongated tubular holder 20, a hinge element 21, a cover or door 22 for the open front of the casing, and contact and latching mechanism which will be described in detail hereinafter. Holder 20, which is constructed of fibrous or other suitable insulating material, is open at the lower end for expulsion of gases therefrom and is closed at the upper end by a removable terminal cap 23. This holder serves to accommodate in a well known manner a circuit interrupting element in the form of a fuse link, the upper end of which link is electrically connected with cap 23, and the lower end or cable extension 24 of which link extends out of the lower end of the holder.

Hinge element 21 has a socket in which the lower end of holder 20 is fixedly secured by means of a screw 25 or other suitable means, and the hinge element has a hook portion 26 engageable with a hinge bracket 27 on the casing for pivotally supporting the switching unit. A resilient finger 28 is attached to the top of the hinge element by means of a screw 29, and the free end 55 of this finger is arranged to bear against the top

of hinge bracket 27 in a manner tending to effect rotation of the switching unit to open position. Cover 22 is of insulation material and has, on the outside thereof, an eyelet handle 32 for manipulation of the switching unit to and from operative position. On the inner side of the cover is a projection 33 having an opening in which holder 20 is fixedly secured by means of screws 34. Thus, in the embodiment of Fig. 1, the hinge element, holder and cover form a rigid switching unit.

The exemplary switching unit shown on the drawing has two combined contact making and latching mechanisms, the upper one of which is supported on terminal cap 23 of holder 20 and the lower one of which is supported on a terminal ferrule 35 fixedly mounted intermediate the ends of the holder. If desired, the upper mechanism also may be supported on a terminal ferrule which is fixedly mounted on the holder and to which the cap 23 is removably secured. The two mechanisms are identical in form so that a description of the upper one, shown in detail in Fig. 3, will suffice to give an understanding of the construction of both mechanisms. On the rear of cap 23 there is secured a plate 36 having a rearwardly extending projection 37 which supports a vertical pivot pin 38. Two contact engaging elements 39 are pivotally mounted on pin 38. The parts of elements 39 which extend forwardly from the pivot point are disposed respectively on opposite sides of cap 23 and have contact portions 40 arranged for engagement respectively with the inner surfaces of the arms of upper contact clip 16. The extreme forward ends of elements 39 are bent inwardly and provided with pins 41 upon which are rotatably mounted rollers 42. Elements 39 cross each other at their pivot point, in the manner of a tongs, and the rearwardly extending arms 43 of the elements have a tension spring 44 connected therebetween. As will be evident from the drawing, this spring biases elements 39 for movement of the contact portions 40 thereof relatively toward each other and out of engagement with the arms of contact clip 16.

For controlling the positioning of the elements 39 of both the upper and lower contact and latching mechanisms, a slide member 47, of insulation material, is mounted on the inner face of cover 22, as shown in Fig. 4. This slide member passes through a slot 48 in door projection 33, and has longitudinal slots 49 engaging screws 50 on the cover. Thus, the slide member is guided for vertical movement on the cover, and two tension springs 51, respectively connected between ears 52 on the slide member and screws 34 on door projection 33, are provided for biasing the slide member downwardly. The upper end of the slide member has a wedge-shaped portion 54 which tapers upwardly and which passes between the rollers 42 of the upper contact and latching mechanism. A similar wedge-shaped portion 55, intermediate the ends of the slide member, passes between the rollers 42 of the lower contact and latching mechanism. A finger 56 is attached to the lower end of the slide member. Normally the slide member is held releasably in its upper position, shown in Figs. 1 and 4, by the fuse link in holder 20, the cable extension 24 of which fuse link is looped under finger 56 and clamped to a depending lug 57 on holder terminal 35.

When slide member 47 is in its upper position, wedge portion 54 maintains the contact portions 40 of upper contact engaging elements 39 rela-

tively spread apart in firm engagement respectively with the arms of upper contact clip 16, as shown in Fig. 3. Similarly, wedge portion 55 maintains the contact portions 40 of lower contact engaging elements 39 relatively spread apart in firm engagement with the arms of lower contact clip 17. Under these circumstances, the arms of contact clips 16 and 17 act as latch detents, and the frictional engagement between these detents and the contact portions 40 of elements 39 is sufficient to maintain the switching unit releasably in its operative position shown in Fig. 1.

Upon rupture of the fuse link in holder 20, due to overload or short-circuit, slide member 47 is released and moves downwardly under the influence of springs 51. The downward movement of the slide member permits the contact portions 40 of the elements 39 of each of the contact making mechanisms, to move relatively toward each other, under the influence of the corresponding one of the biasing springs 44, and out of latching engagement with the arms of the corresponding stationary contact clip. When the latching engagement is released, spring 30 becomes effective to initiate outward swinging of the switching unit and the switching unit finally swings to its dropped-out position, partially shown in Fig. 2, under the influence of gravity. The switching unit, when in open position, may be removed readily from casing 10 by disengagement of hook 26 of hinge element 21 from hinge bracket 27. With a new fuse link installed in the holder, the cable extension of the fuse link is hooked under finger 56 and secured to terminal lug 57 in the manner previously described, so as releasably to hold the slide member in its upper position to maintain contact engaging elements 39 in spread apart positions. Then, upon engagement of hook 26 with bracket 27, the switching unit may be swung into operative position in the manner of a common switch blade.

The embodiment shown in Fig. 5 differs from the embodiment just described, principally in that the casing cover 58 is slidably mounted on fuse holder 20 and has wedges 59 and 60, corresponding respectively to wedges 54 and 55 of the first embodiment, fixedly mounted on the inner side of the cover. For support of the cover on the fuse holder, there are provided on the inner side of the cover, and in vertically spaced relationship, two projections 61 having openings 62 for slidably receiving the holder. A further minor difference in the construction of Fig. 5, over that of Fig. 1, is that the lower stationary terminal 63 and contact clip 64, corresponding respectively to the lower terminal 14 and contact clip 17 of the first embodiment, are mounted at a lower point on the rear wall of the casing in order not to interfere with downward sliding of the cover relative to the holder. The operation of the cutout of Fig. 5, upon rupture of the fuse link in the holder, is the same as that previously described in connection with the cutout of Fig. 1, with the exception that cover 58 slides bodily down so as to cause the wedges 59 and 60 to release the contact engaging elements 39 for inward retraction of the latter relative to each other and out of latching engagement with the arms of the stationary contact clips 16 and 64.

Figs. 6, 7, and 8 show details of a modified form of contact making and latching mechanism which may be employed either at the upper or lower terminal of a cutout such as shown

in Figs. 1 and 2, and a modified form of spreader mechanism. The stationary contact shown in Fig. 6 is adapted to be mounted upon a cut-out casing or other insulating support of a circuit interrupter, and comprises a mounting 5 plate 65 having a U-shaped contact clip 66 and a U-shaped resilient backing clip 67 secured thereto by means of screws 68. Adjacent the outer ends of the contact arms of clip 66, there are formed inwardly extending detent projections 69, and the extreme outer ends of the arms of clip 66 are flared outwardly to provide guide portions 70. Any suitable form of terminal structure may be employed for supporting the contact making and latching mechanism 10 shown in Fig. 6. In the illustrated embodiment, the terminal structure comprises a metallic collar 71 mounted on an insulating fuse holder, indicated at 20, and having a rearwardly extending projection 72. The base of a U-shaped contact clip 73 is secured to projection 72 in such a manner that the arms 74 of this clip extend forwardly in spaced relationship and respectively on opposite sides of terminal collar 15 71 and holder 20. Adjacent the outer ends of arms 74 are formed latching seats 75 for co-operation respectively with detent projections 69 of contact clip 66. The extreme outer ends of arms 74 have forwardly extending lugs 76 for a purpose to be described.

The essential details of the modified spreader mechanism will be apparent from Figs. 7 and 8. This spreader mechanism includes an insulating slide member, inclusively designated 77 in Figs. 7 and 8, which may be slidably supported on the cover of a cutout casing in a manner similar to the slide member in the embodiment of Fig. 1, or which may be slidably mounted in any suitable manner directly on the insulating holder 20 in case the herein described mechanism is employed in an open type circuit interrupter. Slide member 77 is made up of two parallel bars 78 which are constructed of insulation material and the ends of which are seen in Fig. 6. One or more pivot pins 79 are supported by and extend between these bars. Only one pivot pin, disposed at the end of member 77, is shown in the drawing, but it is to be understood that another such pivot pin may be disposed intermediate the ends of the slide member in case two contact making and latching mechanisms are employed as in the cutouts of Figs. 1 and 5. The spreader mechanism includes also two spreader arms 80 which are pivotally mounted at one end on pin 79, and which extend in opposite directions from the pivot pin. The outer ends of these arms have bearing openings 81 pivotally engaging the lugs 76 respectively on arms 74 of contact clip 73.

When member 77 is held in its upper position indicated in Fig. 7, as by means of a fuse link as in the embodiment of Fig. 1, arms 80 are operative to maintain the arms 74 of contact clip 73 spread apart in latching engagement with the arms of contact clip 66, as shown in Fig. 6. Under these circumstances, latching seats 75 are in engagement with detent projections 69 to restrain the fuse holder in an operative position, and a very good electric connection is provided between terminal 71 and the stationary terminal which includes contact clip 66. Member 77 may be arranged to move automatically downwardly under the influence of gravity, or may be biased downwardly by means of springs as in the embodiment of Fig. 1, upon release of

the member due to circuit interrupting operation. Such downward movement of member 77 causes arms 80 to retract clip arms 74 relatively toward each other and out of engagement with the arms of contact clip 66. If desired, clip arms 74 may be resiliently biased in such manner that they tend naturally to move toward each other upon being released by the spreader mechanism.

From the foregoing it will be evident that one of the important features of my present invention is the securing, in a circuit interrupter of the drop-out type, of a highly efficient conductive connection between the stationary contacts and the terminals of the movable switching unit, while rendering movement of the insulating holder of the switching unit unnecessary to effect automatic release of the switching unit from operative position.

The constructions herein described and illustrated are intended to be exemplary only, it being contemplated that there will suggest themselves to those skilled in the art other applications of certain features of the invention and other modifications of the illustrated structures. For example, with some forms of circuit interrupters, it may be desired to dispense with either the upper or the lower of the combined contact making and latching mechanisms and to employ some other means for effecting electric connection between the corresponding stationary contact and switching unit terminal. Hence, it is intended that such other modifications and applications as do not depart from the true spirit of the present invention shall come within the scope of the appended claims.

What I claim as new and desire to secure by Letters Patent of the United States is:

1. In a circuit interrupter, a support having spaced terminals, a switching unit for connection between said terminals including a tubular fuse holder pivoted adjacent one end on said support and a fuse link in said holder, a pair of elements associated with the holder at a point remote from said one end of the holder for engagement with cooperative structure on said support to latch the holder in connected position, said elements being guided for relative movement toward and away from each other, and positioning mechanism for said elements having a part extending along the side of said holder and automatically movable from one position to another position relative to the holder upon rupture of said fuse link, said mechanism maintaining said elements in latching engagement with said structure when said part is in said one position and effecting movement of the elements in opposite directions to release the elements from said structure upon movement of said part to said other position, said part being releasably restrained in said one position by engagement with a portion of said fuse link which extends out of said pivoted end of said holder.

2. In a circuit interrupter, a support, a fuse holder pivoted adjacent its lower end on said support and having spaced terminals for cooperation with spaced terminals on the support, a fuse link in said holder connected between said holder terminals and having a portion extending out of the lower end of the holder, at least one of said holder terminals being located a substantial distance above the lower end of the holder, said one terminal having two contact elements supported for relative movement toward and away from each other and arranged for engagement with cooperative contact structure on

said support, and positioning mechanism for said elements operable to maintain the elements in firm engagement with said structure and operable alternatively to effect movement of the elements in opposite directions so as to release the elements from said structure, said mechanism having a part extending along side of said holder and movable relative to the holder, which said part is engaged by said outwardly extending portion of the fuse link so as to prevent said alternative operation of said mechanism while the fuse link is intact.

3. In a circuit interrupter, a support, a fuse holder pivoted adjacent one end on said support, said holder having a fuse link therein and a terminal located a substantial distance from said one end of the holder, said terminal having a pair of relatively spreadable contact elements, a terminal on said support having a pair of spaced opposed contact surfaces adapted to receive said spreadable elements therebetween, a member extending in substantially parallel side by side relation with said holder and longitudinally movable relative to the holder, a part of said member extending adjacent said pivoted end of the holder, a portion of said fuse link extending out of said end of the holder and engaged with said part so as to restrain said member in one position relative to the holder, said member being automatically movable to a second position relative to the holder upon rupture of said fuse link, means associated with said member to spread said contact elements apart when the member is in said one position, and means to effect movement of said elements relatively toward each other upon movement of said member to said second position.

4. In a circuit interrupter, a support, a fuse holder movably mounted thereon, a fuse link in said holder having a portion extending out of one end of the holder, a contact intermediate the ends of the holder at a substantial distance from said one end of the holder and comprising two elements arranged to engage a cooperative contact on said support, said elements being supported for relative movement toward and away from each other, and mechanism operable to maintain said elements in firm engagement with said cooperative contact and operable alternatively to effect movement of the elements in opposite directions so as to release the elements from said cooperative contact, said mechanism including a member extending in side by side relation with said holder and automatically movable from one position to another position relative to the holder upon rupture of said fuse link, a part of said member extending adjacent said one end of the holder and being interconnected with said outwardly extending fuse link portion so as releasably to restrain said member in its said one position, another part of said member extending adjacent said contact and having means associated therewith for rendering the relative positions of said elements dependent upon the position of said member.

5. In a circuit interrupter, a support, a fuse holder movably mounted thereon, a fuse link in said holder having a portion extending out of one end of the holder, a contact on the other end of the holder comprising two elements arranged for engagement with a cooperative contact on said support, said elements being supported for relative movement toward and away from each other, and mechanism operable to maintain said elements in firm engagement with

said cooperative contact and operable alternatively to effect movement of said elements in opposite directions so as to release the elements from said cooperative contact, said mechanism including a member extending in side by side relation with said holder and automatically movable from one position to another position relative to the holder upon rupture of said fuse link, a part of said member extending adjacent said one end of the holder and being interconnected with said outwardly extending fuse link portion so as releasably to restrain said member in said one position, another part of said member extending adjacent said other end of the holder and having means associated therewith for rendering the relative positions of said contact elements dependent upon the position of said member.

6. In a circuit interrupter, a support, a fuse holder having spaced terminals for cooperation with spaced terminals on said support, a fuse link in said holder connected between said holder terminals, each of said holder terminals having a pair of contact elements for engagement with a contact structure forming part of the corresponding terminal on said support, the two elements of each of said pairs being supported for relative movement toward and away from each other, and mechanism operative to maintain said pairs of elements in firm engagement each with the corresponding one of said contact structures, said mechanism being operable alternatively to effect movement of the elements of each of said pairs in opposite directions so as to release said pairs of elements from said contact structures, said mechanism including a member extending in side by side relation with said holder and automatically movable from one position to another position relative to the holder upon rupture of said fuse link, said member having means associated therewith respectively adjacent each of said pairs of elements for rendering the relative positions of the elements of the respective pairs dependent upon the position of said member.

7. A unitary device for removable installation in an electric cutout or like casing having spaced terminals; said device comprising in combination, a cover for an open side of an electric cutout or like casing, an insulating holder for supporting an automatically operable circuit interrupting means and having spaced terminals for cooperation respectively with spaced terminals in an electric cutout or like casing, at least one of said holder terminals having a pair of contact engaging elements supported for movement relatively toward and away from each other, means operable alternatively to effect movement of said elements relatively apart and to effect retraction of said elements relatively toward each other, and control means for rendering at least a part of the operation of said alternatively operable means dependent upon operation of a circuit interrupting means supported by said holder, said control means comprising a member slidably mounted on said cover in side by side relation with said holder and arranged to move automatically from one position to another position relative to said holder and cover upon operation of a circuit interrupting means supported by the holder.

8. A circuit interrupter comprising in combination, a casing having spaced terminals, a switching unit movably supported on said casing and including a cover for the casing and an insulating holder having automatically operable circuit in-

interrupting means for electric connection between said terminals, said unit having spaced terminals cooperative respectively with said casing terminals, at least one of the casing terminals having a pair of contact members in spaced opposition, the corresponding terminal of said unit having relatively spreadable contact engaging elements receivable between said contact members, spreader means mounted on said cover and automatically movable from one position to another position upon operation of said circuit interrupting means, said spreader means when in said one position being operative to maintain said elements relatively spread apart in firm engagement with said contact members, and means operative to effect movement of said elements relatively toward each other out of engagement with said contact members upon movement of said spreader means to its said other position.

9. A circuit interrupter comprising in combination, a casing having spaced terminals, a switching unit movably supported on said casing and including a cover for the casing and an insulating holder having automatically operable circuit interrupting means for electric connection between said terminals, said unit having spaced terminals cooperative respectively with said casing terminals, at least one of the casing terminals having a pair of contact members in spaced opposition, the corresponding terminal of said unit having a pair of contact engaging elements arranged to be received between said contact members, said elements being spreadable apart relative to each other and being biased relatively toward each other, and wedge means slidably mounted on said cover and automatically movable from one position to another position upon operation of said circuit interrupting means, said wedge means when in said one position being operative to maintain said elements releasably in firm engagement respectively with said contact members.

10. A circuit interrupter comprising in combination, a casing having spaced terminals, a switching unit movably mounted on said casing and including an insulating holder having automatically operable circuit interrupting means for

connection between said terminals, said unit including also spaced terminals cooperative respectively with said casing terminals and a cover for the casing automatically movable from one position to another position relative to said holder upon operation of said circuit interrupting means, at least one of said casing terminals having contact members in spaced opposition, the corresponding terminal of said unit having contact engaging elements spreadable relatively apart and arranged to be received between said contact members, spreader means operative when said cover is in its said one position relative to said holder to maintain said elements relatively spread apart in firm engagement with said contact members, and means operative upon movement of said cover to its said other position relative to said holder for effecting retraction of said elements from their spread apart positions.

11. A circuit interrupter comprising in combination, a casing having spaced terminals, a switching unit including a cover for the casing and an insulating holder having automatically operable circuit interrupting means for connection between said terminals, which said cover is slidably supported on said holder and is automatically movable from one position to another position relative to the holder upon operation of said interrupting means, hinge means adjacent one end of said holder for pivotally supporting said unit, spaced terminals carried by said unit for cooperation respectively with said casing terminals, at least one of the casing terminals having contact members in spaced opposition, the corresponding terminal of said unit having relatively spreadable contact engaging elements biased relatively toward each other and arranged to be received between said contact members, and a wedge on said cover operative in said one position of the cover to maintain said elements in firm engagement respectively with said contact members, said wedge being operative to release said elements for movement of the elements relatively toward each other upon movement of said cover to its said other position.

BENJAMIN R. HERMANN.
